Primary Examiner—B. J. Bullock*Assistant Examiner*—Cheri Cohen[57] **CLAIM**

The ornamental design for a combined scoreboard and interchangeable indicia, as shown and described.

DESCRIPTION

FIG. 1 is a perspective view of a combined scoreboard and interchangeable indicia showing our new design, the broken lines are shown for illustrative purposes only and form no part of the claimed design;

FIG. 2 is a reduced front elevational view thereof;

FIG. 3 is a reduced right side elevational view thereof, the left side being a mirror image; and,

FIG. 4 is a reduced top plan view thereof.
